UNITED STATES PATENT OFFICE.

ELISA LEWY, OF NEW YORK, N. Y.

CORSAGE-BOUQUET HOLDER.

1,210,957.

Specification of Letters Patent. Patented Jan. 2, 1917.

Application filed April 23, 1915. Serial No. 23,287.

To all whom it may concern:

Be it known that I, ELISA LEWY, a citizen of the United States, residing in the city, county, and State of New York, have invented new and useful Improvements in Corsage-Bouquet Holders, of which the following is a specification.

This invention relates to improvements in holders for corsage bouquets and the objects 10 of the invention are the provision of a holder which will securely grip the bouquet or flowers placed therein irrespective of the size of the same, within reasonable limits, and also to prevent the displacement or dis- 15 tortion of the holder with respect to the corsage.

The invention is fully set forth and described in detail in the accompanying specification and drawings forming a part there- 20 of, in which—

Figure 1 is a perspective view showing one form of the holder; Fig. 2 is an elevation of a blank from which the holder shown in Fig. 1 is constructed; Fig. 3 is a rear view 25 of the construction shown in Fig. 1 slightly modified; Fig. 4 is a front elevation of a further modification; Fig. 5 is a cross section along the line 5—5 of Fig. 4; Fig. 6 is a cross section of a still further modification.

Referring to the drawings, which for convenience show the holder upon an enlarged scale, and the construction shown therein, the reference numeral 1 designates the central web of a metal blank, preferably 30 of German silver or other suitable spring metal, the same being provided at its top and bottom with integral, oppositely extending gripping members 2 and 3. Intermediate said gripping members the said central web is provided with oppositely extending bars, 4, 4' and 5, 5', the ends 4 and 5 thereof being provided with ears *a* and *b*, respectively, which as shown in Fig. 2 are struck up to form a bracket adapted to receive the pivots *c* which retain pin members 35 6, 6' in position while permitting of the horizontal movement thereof. The bars 4', 5' as shown in Fig. 2 are provided with ears *d* which are adapted to be formed into hook members *d'*.

The barb 7 is struck up from the central web, the same being adapted to pierce the upper portion of the bouquet when inserted in said holder and thereby more securely

hold the same against displacement there- 55 from.

In Fig. 3 is shown a modification in which the upper gripping members 2' are provided with spring hinges *e* in lieu of having the same integral with the central web. This 60 construction is advantageous when the metal does not possess sufficient elasticity to permit of the gripping members being readily opened and also to elastically grip a bouquet when inserted therein, as for example, when 65 it is desired to make the same out of sterling silver or gold.

In Fig. 4 is shown a further modification, in which in lieu of bar pins for securing the holder to the corsage, I have provided spring 70 clips 8, the same being also secured to the central web by means of spring hinges *e'* corresponding to the spring hinges *e*, shown in Fig. 3 for securing the gripping members to the central web. These clips are provided 75 with thumb pieces 9 for operating the same and it is obvious that by compressing the said thumb pieces 9 the clips will be opened, and then by releasing the same the barbs *f* will grip the fabric of the corsage so as to 80 securely retain the holder in position.

In Fig. 6 I have shown a still further modification in which the body 10 of the bar pin is soldered to the central web 1 of the holder in lieu of having the same formed 85 integral with said web.

The operation of the holder as is obvious from the foregoing description, consists merely in forcibly opening the spring gripping members shown in Figs. 1, 2, 4, 5 and 90 6 or the spring gripping members shown in Fig. 3 and inserting the bouquet so that the barb 7 pierces the same. Then either the bar pin, as shown in Figs. 1, 3 and 6, is secured to the corsage or the spring clips 8 95 are caused to pierce the fabric of the corsage and grip the same so as to prevent displacement of the holder until the said pin members or clips are positively withdrawn from the corsage.

The foregoing construction provides an extremely simple and yet effective and economical device for the purpose intended and one which can be readily retained in the exact position desired upon the corsage, 105 which feature, as must be obvious to one familiar with the requirements of these devices, is a highly important one. Moreover the

central web serves as an efficient protector to prevent soiling of or injury to light fabrics by the stems of the flowers or the briars or thorns thereon or from the wrappers such as 5 tin foil used therewith.

Having thus described my invention, what I claim and desire to secure by Letters Patent is:—

10 A corsage flower holder comprising a longitudinal strip of metal provided with two pairs of oppositely extending over-lapping arms integral therewith, each pair being positioned at the opposite ends of said strip, two oppositely extending pairs of pin sup-

ports also integral with said strip adjacent each end thereof, a pin member pivotally secured to one member of each pair, the free end of said pin members being adapted to be retained by the free end of the opposite member of each of said pairs of pin supports, and an integral barbed member struck up from said strip and projecting at an angle therewith.

In witness whereof, I have hereunto set my hand at the city, county and State of 25 New York, this 22nd day of April, 1915.

ELISA LEWY.
